UNITED STATES PATENT OFFICE.

FREDERICK W. DOHM, OF ST. PAUL, MINNESOTA, ASSIGNOR OF ONE-FOURTH TO JAMES C. BRAMWELL AND ONE-FOURTH TO DARIUS F. REESE, BOTH OF ST. PAUL, MINNESOTA.

CURTAIN-ROD BRACKET.

1,057,043.

Specification of Letters Patent. Patented Mar. 25, 1913.

Application filed January 30, 1909. Serial No. 475,289.

To all whom it may concern:

Be it known that I, FREDERICK W. DOHM, a citizen of the United States residing at St. Paul, in the county of Ramsey and State 5 of Minnesota, have invented certain new and useful Improvements in Curtain-Rod Brackets, of which the following is a specification.

My invention relates to improvements in 10 curtain rod supports its object being to provide a reversible curtain rod support which may be used equally well upon the inner or outer side of a window frame to support the curtain rod.

15 To this end my invention consists in the features of construction and combination hereinafter particularly described and claimed.

In the accompanying drawings forming 20 part of this specification, Figure 1 is a perspective view of my improved curtain rod supports shown in connection with a curtain rod, Fig. 2 is a top elevation showing the supports arranged inside the window 25 frame, Fig. 3 is a similar view showing the supports or brackets arranged on the outer side of the window frame, and Fig. 4 is a section of one of the brackets on line $x-x$ of Fig. 1.

30 In the drawings A represents one of a co-operating pair of curtain rod supporting brackets and B represents the other bracket. C represents an ordinary curtain rod.

The bracket A comprises two connected 35 walls 2 and 3 standing at right angles with each other and each formed with openings 4 through which suitable securing means may be passed to support the bracket upon the window frame. Extending inwardly from 40 the wall 3 parallel to the wall 2 is a socket 5 to receive one end of the curtain rod. The co-operating bracket B is similarly composed of two connected walls 6 and 7 standing at right angles with each other and each 45 formed with openings 8 through which securing means may be passed to fasten the bracket to the window frame. Secured to the wall 7 and extending inwardly alongside of the wall 6 is a socket piece 9 to re-

ceive the adjacent end of the curtain rod. 50 The socket piece 9 is open on its forward side to allow the end of the curtain rod to be dropped into, or lifted therefrom.

In use, where it is desired to support the rod inside the window frame D, as shown in 55 Fig. 2, the brackets A and B are secured to the opposed inner sides of the frame by screws 10 or similar securing means passed through the openings in the walls 3 and 7 of the brackets. The curtain rod may 60 then be placed in position by inserting one end of the rod in the socket piece 5 and dropping the other end into the socket piece 9. Where it is desired to support a curtain rod outside the frame as indicated in 65 Fig. 3 the brackets are supported upon the outer faces of the frame by passing securing means through the openings in the walls 2 and 6 of the brackets. Thus the same brackets may be used to support a curtain 70 rod on either the inside of the window frame or upon the outside, rendering unnecessary the use of different sets of curtain rods as in ordinary practice.

I claim as my invention:

Means for supporting a curtain rod in 75 connection with a frame comprising a pair of brackets, each bracket consisting of two similar walls connected with each other at right angles, an open ended socket piece carried upon the inner side of one bracket wall and extending inwardly across the inner face of the connected wall, a socket piece 80 carried by the inner face of one inner wall of the co-operating bracket 85 and, extending inwardly across the inner face of the connecting wall, said socket piece having an open front whereby to form a top and bottom part of the socket piece above the curtain rod when in position 90 thereon.

In testimony whereof I affix my signature in presence of two witnesses.

FREDERICK W. DOHM.

Witnesses:

H. SMITH,
H. S. JOHNSON.
